UNITED STATES PATENT OFFICE.

WARREN R. CLIFTON, OF SHARON, PENNSYLVANIA.

SAFETY DEVICE FOR BLAST-FURNACES.

No. 867,244.

Specification of Letters Patent.

Patented Oct. 1, 1907

Application filed May 1, 1907. Serial No. 371,324.

To all whom it may concern:

Be it known that I, WARREN R. CLIFTON, a citizen of the United States, residing at Sharon, Pennsylvania, have invented certain new and useful Improvements 5 in Safety Devices for Blast-Furnaces, of which the following is a specification.

The ordinary blast furnace is filled from the top at regular intervals with materials to be melted and reduced for the purpose of manufacturing pig iron. The 10 reduction is effected by hot blast (air) which is forced into the bottom of the furnace, through tuyers, by means of blowing engines. This melting and reducing process at the bottom of the furnace causes the materials to descend from the top to the bottom down 15 through the furnace so long as the process of reduction is carried on at the bottom. At times the material will arch or scaffold (called "hanging") in the furnace and allow the material to melt away from the bottom. This scaffold breaking away from the sides or middle 20 (called "slipping") causes a rush of gases up through the column of material which endangers the wrecking of the furnace and the loss of life to the workmen by the materials being thrown out at the top of the furnace. The first warning the workmen have of the scaffold material 25 breaking away, or slipping down (called "slip") is when the gases and material are thrown out at the top of the furnace and scattering the material all over the surrounding country. This warning, of breaking away and slipping, is too late to allow the furnace man to 30 check the force of the slip. The present method of checking the force of the slip is for the furnace man to order the blowing engines or air pumps slackened down, but this is not ordered done until the furnace man has seen the gases and materials pouring or flying out at the 35 top of the furnace when it is too late as the damage has already been done.

The object of my present invention is to reduce or cut off the admission of blast, at the instant the slip occurs by automatic means.

40 An embodiment of my invention is illustrated in the accompanying drawings, in which,

Figure 1 is a sectional elevation, and Fig. 2 a sectional plan.

In this drawing A designates a blast furnace of the ordinary or any desired form, and A' the tuyers which 45 are supplied with the hot air blast through pipe A² from the hot blast ovens or stoves A³ in the usual manner. B is the pipe which supplies the air blast to the stoves, the blast being created by blowing engines in the ordinary or any desired manner. This pipe has an 50 open branch B' which in the normal operation of the furnace is closed by a valve B². A branch pipe or passage C from the upper part of the furnace has an element therein designed to be moved under excess of pressure in the furnace and through suitable connec- 55 tions operate the valve B².

Preferably the passage has a cylindrical portion in which moves a piston C' which when it is raised by the pressure produced by a violent explosion in the furnace, pulls up the connecting rod or rope C² and thus 60 instantly opens the valve B² and reduces or cuts off the air blast to the furnace.

Having thus described my invention what I claim is:

1. The combination with a blast furnace, of a blast 65 controlling device, and means for automatically operating said device upon the occurrence of an explosion in the furnace, substantially as described.

2. The combination with a blast furnace, of a blast 70 controlling device, an element connected with the furnace and movable under the excessive pressure produced by an explosion within the furnace, and a connection between said movable element and the controlling device, substantially as described.

3. The combination with a blast furnace, blast heating 75 stoves, and cold and hot blast pipes, of a passage leading from the cold blast pipe to the atmosphere, a valve in said pipe, and means actuated by excessive pressure in the furnace for opening said valve, substantially as described.

In testimony whereof, I affix my signature in presence of 80 two witnesses.

WARREN R. CLIFTON.

Witnesses:
JOHN E. ORR,
C. P. SPECHT.
